UNITED STATES PATENT OFFICE

2,332,184

EXERCISING APPARATUS

John P. Sweeney, Chester, Pa.

Application July 20, 1940, Serial No. 346,478

4 Claims. (Cl. 128—25)

My invention relates to a new and useful exercising apparatus and has for one of its objects to provide a simple and effective device of this character for use by persons desiring or requiring physical exercises, especially indoors. This apparatus is particularly adapted for use in the home, and therefore must be compact and collapsible to some extent, in order that it may be stored within a small space, for example, under a bed.

Another object of the invention is to construct an adjustable exercising machine that may be readily and easily regulated to accommodate its use to persons of different heights.

Another object of the invention is to provide an apparatus of this kind which may be operated manually or mechanically in order to permit different forms of exercising.

Another object of the invention is to provide an exercising device on which a person may take a dry swim, thus exercising and stretching all of the muscles of the body, including those of the stomach, arms, wrists, hands, fingers, thighs, lower legs, ankles and feet, without any cramping effects. In employing the apparatus for exercising purposes, the user lies on his stomach, thus imparting a massaging action which tends to break down the globules of fat, thus assisting in the elimination of excess fat.

Another object of the invention is to provide an exercising apparatus including hand and foot cranks connected for simultaneous operation through manipulation of either of said cranks and having associated means for producing pressure thereon.

Another object of the invention is to provide a rest or table on which the user lies and to employ means for imparting a regular lateral oscillation or tilting action thereto.

A further object of the invention is to provide a motor driven mechanism for actuating the cranks and table or rest.

A still further object of the invention is to provide a telescopic tubular casing and shaft section.

With the above and other objects in view, this invention consists of the details of construction and combination of elements hereinafter set forth and then designated by the claims.

In order that those skilled in the art to which this invention appertains may understand how to make and use the same, I will describe one form of its construction in detail, referring by numerals to the accompanying drawings forming a part hereof, in which—

Fig. 1 is a side elevation of the apparatus embodying my invention.

Fig. 2 is an enlarged view of one end of the gear box taken on the line 2—2 of Fig. 1.

Fig. 3 is an enlarged sectional view of said gear box on the line 3—3 of Fig. 10.

Fig. 4 is a top plan view of the apparatus with some parts broken away and other parts shown in section to illustrate details of construction.

Fig. 5 is an enlarged longitudinal sectional view of a portion of the main shaft assembly, the shaft elements being illustrated in elevation.

Fig. 6 is an enlarged sectional view on the line 6—6 of Fig. 5.

Fig. 7 is an enlarged sectional view on the line 7—7 of Fig. 5.

Fig. 8 is an enlarged sectional view on the line 8—8 of Fig. 5.

Fig. 9 is a longitudinal sectional view of another portion of the main shaft.

Fig. 10 is an enlarged longitudinal sectional view of the gear box and adjacent elements and the pressure cylinder.

Fig. 11 is a front end view of the apparatus.

Fig. 12 is a rear end view thereof.

Fig. 13 is a top plan view of the rest or table with a portion of the cushion broken away.

Fig. 14 is an end view thereof and showing an arrangement for mounting the same and the means for oscillating it.

Fig. 15 is an enlarged fragmentary sectional view of one of the cranks and the crankshaft to which it is connected.

Fig. 16 is a section on the line 16—16 of Fig. 15.

Fig. 17 is a detail view partly in section and partly in elevation of the elements constituting the clutch for placing the apparatus in condition for either manual or mechanical operation.

Fig. 18 is a view of one end of the movable clutch member.

Fig. 19 is an opposite end view thereof.

Fig. 20 is a section on the line 20—20 of Fig. 17.

In carrying out my invention as herein embodied 25 and 26 represent two trestles or horses mounted on the ends of the cross-piece 27 and having legs 28 connected thereto, preferably by pivots 29, whereby said legs may be folded up to make a compact structure for storage purposes. It will be obvious that any equivalent means for connecting the legs to the trestles may be utilized such as having them removably attached to said trestles. The trestles, cross pieces 27 and the legs 28 constitute the supporting frame of the exercising apparatus.

55 The trestle 25 carries an upwardly projecting

support 38, the cross piece 27 also carries an upwardly projecting support 31 and likewise the trestle 26 carries an upwardly projecting support 32 embodying a split clamp 33 which is closed by a suitable lever 34. The supports 30 and 31 are formed with the sockets 35 and 36 which in turn are formed with or carried by the side arms 37 projecting from opposite ends of the gear housing 381. As plainly shown in Fig. 4, the arms 37 are laterally spaced so that there is a wide open area between each pair of them, each of said areas, in particular, being formed by an end of the gear box, a socket, and one pair of arms.

In one of the sockets, as 35, is mounted an end 10 of a tubular casing 38 which, in this particular instance, is the forward tubular casing, and the opposite end of said casing is set into the socket element 39 of the front crank housing 40 which includes oppositely projecting arms 41 and said front crank housing has an opening leading to the interior thereof at the junction of the socket elements and said arms, which opening is closed by a detachable cover 42.

In the other gear box socket 36 is mounted one end of an outer tubular casing 43, the other end being mounted in the socket portion of the support 32. Passing through the clamp element 33 of the support and telescoping into the outer tubular casing 43 is an inner tubular casing 44 which can be slid in and out as desired and held in an adjusted position by the split clamp 33. The outer end of the inner tubular casing 44 is set into the socket element 45 of the rear crank housing 46, including oppositely projecting short arms 47 with an opening at the junction of said arms and the socket element, which opening is normally closed by the removable cover 48.

The main drive shaft section 49 is mounted in a suitable bearing in the socket element 39 of the front crank housing and projects into said housing with a bevel gear 50 fixed on said projecting end to mesh with the bevel gear 51 fixed to the crankshaft 52 journalled in suitable bearings 53 mounted in the arms 41 of said front crank housing. The ends of the crankshaft 52 are squared as at 54, in Fig. 15, or otherwise fashioned to receive the crank arms 55 including rotatable handles or grips 56.

The inner or rear end of the main or drive shaft section 49 is fixed to a coupling 57, Fig. 10, to which is also fixed one end of the main or drive shaft section 53 passing longitudinally completely through the gear box 381 and the opening in the gear box which provide for the accommodation of the main shaft section 53 are closed by suitable packing glands 59, one at each end of said gear box.

The other or rear end of the main or drive shaft section 58 is fixed in a coupling 60, Fig. 5, to which is also attached the stub 61 carried by one end of the hollow main or drive shaft section 62, and the opposite end of said hollow drive shaft section has a polygonal opening 63 formed therein, either by shaping the hollow shaft section itself or by welding a piece thereto which has polygonal interior formation.

Projecting through the polygonal opening 63 and telescoping into the hollow shaft section 62 is a polygonal shaped main or drive shaft section 64 having its outer end round for journalling in the bearing 65 mounted in the socket element 45 of the rear crank housing 46. Said shaft section 64 projects into the rear crank housing 46 and has a bevel gear 66 mounted thereon and

meshing with the bevel gear 67 mounted intermediate the ends of the shaft 68 and journalled in suitable bearings in the rear crank housing 46, all similar to the assembly shown in the front crank housing. The ends of the crankshaft 68 have the crank arms 69 secured thereto and said arms carry rotatable pedal members 70 which may be similar to the handles 56, or in the shape of bicycle pedals, or stirrups.

On the section of the main or drive shaft with- 10 in the gear box so as to freely revolve thereon, is mounted a worm 71 which meshes with a worm gear 72 keyed or otherwise fixed to the cross shaft 73 suitably journalled in the gear box, and having one end protruding on which is mounted a cam 74 encircled by the follower 75 carried by the piston rod 76 projecting into the cylinder 77 of a suitable compressor, fixed, as at 78, to a portion of the frame. This compressor, or the cylinder thereof, contains a suitable fluid and where the piston rod enters said cylinder it is made fluid tight by a suitable packing box or gland 79. On the inner end of the piston rod 76 is a piston 80 for reciprocation and to force the fluid therein from one side of the piston to the other through the pipe line 81 connecting both heads of the cylinder and said pipe line has a valve 82 interposed therein in order to regulate the speed at which the fluid may pass from one end to the other of the cylinder.

With this pipe line is also connected a gauge 83 located in any suitable or convenient position to be viewed by the user of the apparatus while manually operating the same.

On the section of the main or drive shaft with- 20 in the gear box and freely revolvable thereon, is mounted the worm gear 84 which meshes with a worm 85 keyed or otherwise fixed to another cross shaft 86 which has an end projecting outside of the gear box opposite to the shaft 73. Since both of the cross shafts 73 and 86 project from the gear box, and as the latter is to contain a suitable lubricant for the gears, said shaft and gear box are provided with packing boxes or glands 87.

On the outer end of the cross shaft 86 is mounted a pulley 88, preferably of the two speed or multiple type which is in line with a similar pulley 89 on the shaft 90 of the motor 91 or other suitable prime mover. The outer end of the shaft 90 may be supported in a pedestal 92, and said pedestal and motor 91, may be mounted on a plate 93 carried by the frame of the apparatus. A belt 94 passes around both of the pulleys 88 and 89 and may be shifted from one groove to another for changing the speed at which the cross shaft 86 is to be revolved, thereby regulating the speed of the main or drive shaft. Of course it will be obvious that any other means for driving the cross shaft 86 may be used, such as a train of gears or sprockets and a chain.

The worm 71 and the worm gear 84 which are loosely mounted on the main or drive shaft are in spaced relation, and between them is a movable clutch member 95 which is keyed to the main or drive shaft so as to slide thereon and revolve therewith and adapted to be selectively engaged with either the worm or the worm gear. Both the worm 71 and the worm gear 84 have a projection 96 with opposite flat faces to fit the respective oblong openings 97 in opposite ends of the movable clutch member 95.

In mounting these parts, it is preferable that a bushing 98 be placed upon the main or drive shaft so as to engage one end of the gear box

381 as shown in Fig. 10. The worm gear 71 is then mounted on the shaft and a circular bushing or washer 93 placed over the shaft and engaged with the end of the projection 96 on said worm 71. Next the keys 97a are placed in the keyways of the shaft so as to engage the bushing 99 and the movable clutch member 95 having corresponding keyways 100 slipped into place. Next another circular bushing or washer 101 is placed on the shaft and movable into engagement with the opposite ends of the keys. Thereafter the worm gear 84 is placed on the shaft so that its projection 98 engages the bushing 101 and finally the bushing 102 is placed on the shaft between the worm gear 84 and an end of the gear box.

With the parts assembled in this manner, whenever the movable clutch member 95 is moved towards the right hand side, or forwardly, as shown in Figs. 10 and 17, said movable clutch member is clutched to the worm gear 84 and therefore power and motion may be transmitted from the motor 91, the pulleys and belt, the cross shaft 86, the worm 85 and the worm gear 84 to the main or drive shaft. But if said movable clutch member is moved towards the left, it will engage the worm 71 and when the cranks are turned motion can be transmitted from the main or drive shaft through the clutch, said worm 71, the worm gear 72 and cross shaft 73, and the cam to the compressor, which will make it necessary for the operator to use considerable force to overcome the pressure of the compressor, and such force will be registered on the gauge 83, indicating the amount of energy expended, and by noting the same, the operator may keep a record of his progress.

The gear box may have a top opening normally closed by a removable cover 103 and this may carry a slidable clutch operating rod 104 having a fork 105 attached thereto which registers with an annular groove 106 in the movable clutch member. Projecting from the supports 30 and 31 and especially the socket portions 35 and 36 respectively, are brackets 107 located between pairs of ears 108 depending from the underside of the longitudinal center of the body rest or table 109 and pins 110 are projected through said ears and brackets to pivotally mount said body rest or table. In order to permit the use of light weight material for the manufacture of the body rest or table and still have it sufficiently strong to support considerable weight and stand much hard usage, longitudinal and transverse ribs 111 may be formed on the underside thereof.

One of the ears of one pair may be produced of sufficient length for cooperation with another ear 112 through which passes a pin 113 for pivotally connecting one end of the cam follower 114 with said body rest or table and the other end of said follower engages the cam 115, Fig. 10, fixed to the main or drive shaft, as by a key 116a, within the space between a pair of the arms 37. In order to protect the body of the operator while using the apparatus, a cushion 116 of any suitable material is mounted on top of the body rest or table 109.

Whenever the main or drive shaft is revolved, either manually or mechanically, the cam 115, through its follower 114 will oscillate the body rest or table laterally as indicated by the dotted lines in Figs. 11 and 12.

From the foregoing description of the construction and operation of the exercising apparatus, it will be apparent that a person gripping the

handles and having the feet in engagement with the pedal members, can turn the forward crank with the hands and the rear crank with the feet, in approximately the correct rhythm for swimming, at the same time imparting a rolling action to the body as in the case of a swimmer. Different types of swimming strokes may be simulated by various changes in the relations of the arms of the front and rear cranks, which can be readily accomplished by resetting the arms on the crank-shafts.

Such exercises will develop the muscles of the operator's body as much as or more than when walking, running, bicycle riding or hill climbing and at the same time teach the correct use of strokes for swimming.

Also, the operator may sit on the table with feet and legs free and may effect a rowing motion by adjusting arms 55 so that they are both mounted on the same side of the crankshaft 52; or the operator may sit erect on the table facing the rear end, with hands and arms free and effect a bicycling motion; or the operator may lie on his or her back on the table, operating with feet only, which will exercise the lower muscles of the body, hips, etc.

Of course I do not wish to be limited to the exact details of construction herein shown and described, as these may be varied within the scope of the appended claims without departing from the spirit of my invention.

Having thus described my invention, what I claim as new and useful is:

1. An exercising apparatus comprising a frame, a longitudinally telescopic casing including a gear box, a sectional telescopic main shaft mounted in said casing, cranks mounted in the ends of said casing and geared to the main shaft, a worm gear loosely mounted on the main shaft within the gear box, a cross shaft journaled in said gear box with a portion of said cross shaft protruding from one side of the gear box, a worm on said cross shaft within the gear box and meshing with the worm gear, a clutch to selectively connect the worm gear with the main shaft, a pulley on the protruding end of the cross shaft, a motor including a shaft, a pulley on the shaft of the motor, a belt engaging said pulleys, and a body rest pivoted to the frame and positioned above the casing between the locations of the cranks.

2. The structure in claim 1, in combination with a cam on the main shaft, and a follower pivoted to the underside of the body rest and engaging the cam to oscillate said body rest as the main shaft is revolved.

3. In a device of the kind described, a frame, a gear box, pairs of spaced arms projecting from both ends of said gear box, a socket at the outer end of each pair of arms, means connecting the sockets with the frame, a forward tubular casing member having an end mounted in one of said sockets, a front crank casing on the outer end of said casing member, a crank journaled in said front crank casing, a bevel gear fixed to said crank, a main shaft section mounted in said casing member, a bevel gear on said main shaft section and meshing with the first mentioned bevel gear, a second main shaft section mounted in the gear box, means to couple one end of the second main shaft section to the first mentioned one, an outer casing member having one end mounted in the other socket of the gear box, an inner casing member telescoping in the outer casing member, means to hold the inner casing member in any adjustment, a hollow main shaft sec-

tion having a polygonal opening at its outer end, a stub shaft at the other end of said hollow shaft section, means to couple said stub to the second main shaft section, another main shaft section having a long polygonal portion telescoping into the hollow section through its polygonal opening, a bevel gear on the outer end of the last named shaft section, a crank casing on the outer end of the inner casing member, a crank journalled in said crank casing, a bevel gear fixed to said crank and meshing with the gear on said last named main shaft section, a worm and a worm gear loosely mounted on the second main shaft section within the gear box, a clutch to selectively clutch the worm and the worm gear

to the main shaft, a cross shaft journalled in the gear box, a worm gear thereon meshing with the worm on the main shaft, a compressor, means to operate said compressor from the cross shaft, a second cross shaft journalled in the gear box, a worm thereon meshing with the worm gear on the main shaft, means to drive said second cross shaft, and a body rest pivoted to the frame above the gear box.

5 10 15 4. The structure in claim 3, in combination with a cam on the main shaft section between one pair of gear box arms, and means connecting said cam and body rest to oscillate the latter when the main shaft is revolved.

JOHN P. SWEENEY.
